UNITED STATES PATENT OFFICE.

ELIHU THOMSON, OF SWAMPSCOTT, MASSACHUSETTS, ASSIGNOR TO THE GENERAL ELECTRIC COMPANY, OF NEW YORK.

METHOD OF AND APPARATUS FOR CONVERTING ELECTRIC CURRENTS.

SPECIFICATION forming part of Letters Patent No. 595,419, dated December 14, 1897.

Application filed February 27, 1897. Serial No. 625,813. (No model.)

To all whom it may concern:

Be it known that I, ELIHU THOMSON, a citizen of the United States, residing at Swampscott, in the county of Essex, State of Massachusetts, have invented certain new and useful Improvements in Methods of and Apparatus for Converting Electric Currents, (Case No. 512,) of which the following is a specification.

10 My present invention relates to the working of high-potential apparatus from such circuits as those used for continuous-current lighting or circuits which have a definite direction of current at constant potential.

15 My invention consists, broadly, in energizing a magnetizable core by a coil acting as a primary fed from the mains, inductively substituting for this coil at the moment of rupture of its circuit a second primary (which

20 may be called a "secondary primary") of low potential, accumulating by induction in the second primary on closed circuit a vigorous charge and at the proper interval breaking the secondary primary with or without a con-

25 denser across the point of rupture, whereby the secondary primary becomes virtually a low-potential primary traversed by a heavy current which is suddenly interrupted, and the interruption of which reacts vigorously

30 upon the other windings around the core to set up in them high potentials.

In the accompanying drawings, Figure 1 is a diagrammatic view of an arrangement, showing the coil in section and the connections to the different commutating devices. Fig. 2 is a diagram of circuit connections embracing a modified form of Fig. 1. Fig. 3 is a view of a suitable commutator. Figs. 4 and 5 are further modifications. Fig. 6 is an arrangement 35 by which all of the fine winding may be used to furnish the inductive discharge. Fig. 7 is a view of an insulating device for the commutator, and Figs. 8 and 9 are diagrams of circuit connections.

45 In Fig. 1, *m n* represent the terminals of the line, which may be assumed to be of one hundred to two hundred volts potential. A branch taken from this line feeds the primary *P'* around the core *C*, in which may be used, if 50 desired, a regulating-resistance *R*. The primary *P'* has a considerable number of turns

and is of comparatively small wire, the object being to charge the core *C* magnetically within an interval of time more or less great. If it is to be done in a short time, the winding 55 *P'* is made coarse, but if in a longer time the winding *P'* should be finer. The circuit of the winding *P'* is closed at intervals by a commutator *G*, upon which rests a brush *B'*. On the rupture of the circuit, when the segment 60 *G* in revolving leaves brush *B'*, the brush touches the following segment *f*, insulated from the first and connected to one terminal of the condenser *F*, the other terminal of which is connected to a line *a*, leading to segment 65 *G*. On the same shaft with segment *G* and electrically connected with it is mounted a second segment *G²*. This segment *G²* is followed by the condenser-segment *f*, and brush *B²* slides on these segments successively. *B²* 70 makes contact with segment *G²* at or about the time that segment *G* breaks contact with brush *B'*. Brush *B²* is one terminal of a heavy coil *P²*, wound upon the core *C*, in close inductive relation to coil *P'*. It may be called the 75 "secondary primary" coil. Outside of these coils is the ordinary secondary winding *s s* of an induction-coil, the terminals *t t* being separated. A spark *D* is shown between them. The return connection from the coil *P'* to the 80 line *m* is indicated at *b*.

The operation of the device is as follows: The closure of contact of segment *G* with brush *B'* permits current to pass through a circuit from *m*, through connection *b*, through 85 coil *P'* to brush *B'*, to segment *G*, to connection *a*, to resistance *R*, to line *n*. The current during the revolution of segment *G* begins at a low value, being opposed by inductance of coil *P'*, and gradually rises to its 90 maximum. At this moment it is broken by the revolution of the segment *G*, which leaves *B'*. As the segment *G* leaves the brush *B'* segment *f* is substituted. The condenser *F* is thus thrown across the break. Meanwhile, 95 however, at the moment of breaking contact between *G* and *B'* segment *G²* comes into contact with brush *B²*, closing the circuit of the secondary primary *P²* for a short interval, during which there is induced by the rupture 100 of the primary *P'* a heavy current in the coil *P²*, representing in fact almost the entire en-

ergy of the circuit P' , transferred to P^2 instantaneously as a substitute circuit. As soon as this current has reached its full value it is broken by the rupture of G^2 with brush 5 B^2 , and the condenser is again, by segment f , thrown across the break of the secondary primary circuit. The immediate effect is the collapse of the magnetism of the core C and the production of an intense inductive effect 10 in all the windings. One of these is the work-circuit $S S$, the normal secondary of the induction-coil, in which it manifests itself by a great rise of potential at the terminals, and if these are not too distant a spark is produced, or if vacuum-tubes be used an illumination and discharge from the secondary circuit occurs. While this action is occurring and rapid makes and breaks take place at the break-piece, there is only a slight spark 15 produced there, because the rupture of the high-potential primary, which would ordinarily be attended by a flaming and spark, is made at or about the time when the secondary primary P^2 is a closed circuit. This 20 action kills the inductance of P' (upon which its sparking depends) and allows the current to be suddenly cut off in it. Whatever slight spark might be produced is taken care of by the condenser F . Some inductance of course 25 remains, owing to the fact that the coil P^2 cannot be so completely intermingled with the coil P' as to practically occupy the same space.

Fig. 2 shows in a diagrammatic way the 30 same elements as before, but shows also that the coil P , which is the first primary, may also act as part of the coil $s s$ of Fig. 1 and become the discharging secondary. This is particularly the case when the potentials between m and n are considerable, as when it is 35 two hundred and twenty or five hundred volts. In this case the turns of the coil P may be very many. For example, for a moderate-sized apparatus they may be ten thousand to 40 twenty thousand turns, the turns at P^2 being made, as before, very few and relatively coarse. The action on the closure of circuit P is to pass an increasing current up to full value from the mains $m n$, which is cut off by 45 segment G leaving the brush B' . At the same moment the circuit of coil P^2 is closed, and the energy is transferred immediately thereto. This is afterward followed by the rupture of the coil P^2 and its reaction on the fine-wire 50 coil P , with the consequent production of high potentials at the terminals $t t$. In this case it is desirable that the break-piece be well insulated and at least the brush B' and segment G operated in oil or other insulating fluid. 55 Where, however, the potentials developed are not sufficient to require this precaution, the break-piece may take the form shown in Fig. 3, where the segment G is prolonged to the left to form the tongue G^2 , upon which the brush B^2 bears, while B' bears upon G , as before. The condenser-segment f has a strip 60 which is common to both brushes B' and B^2

and immediately follows the segment G . The segment G is connected by a brush H^2 to the other parts of the circuit. This brush rests 70 on a ring h^2 , while on the other side is a brush H' , having a similar office for the condenser-segment f . All the parts of the apparatus otherwise are thoroughly insulated.

Fig. 4 shows that if the potential of the coil 75 P^2 be made low enough—that is, if its winding be made of very few turns—then the condenser might be dispensed with, provided the potential set up on the rupture of the circuit P^2 is so low as not to involve destructive spark. 80 In this case all that is necessary is to provide for a good closure of the terminals of P^2 by a contact-maker G^2 , which follows immediately upon the rupture by brush B' from segment G , in circuit with the coil P , this action again 85 being followed by rupture of circuit P^2 soon after.

Fig. 5 shows a form of my invention in which the coil P' is energized, as before, from connections to the mains $m n$, taken from the 90 line through brush B' , segment G , and brush H^2 , and having a condenser F and condenser-segment f , related as before. The circuit of coil P^2 —that is, the substitute circuit—is in this case not closed metallically, but through 95 a condenser F^2 of limited capacity by brushes $B^2 B^2$, resting upon a contact device G^2 , the connection of which follows the contact-breaking in the circuit of P' either immediately or at about the same time. In this case the coil 100 P^2 may be made of fine wire of many turns, and the condenser F^2 furnishes for it a circuit virtually closed, but for a limited time. The discharge of the coil P^2 finds a substitute path or substitute circuit for the energy in P' — 105 that is, on the rupture of the circuit P' by the brush B' and segment G , the circuit of P^2 having been closed, current flows in it, which charges the condenser F^2 , which permits the rupture of the first circuit P' substantially 110 without spark. As the condenser F^2 has but limited capacity, the circuit P^2 is virtually broken, or at least the current therein is stopped and suddenly reversed, by the discharge of the condenser, thus giving the effect 115 of an actual break, which may be utilized as is the break in the former figures.

Fig. 6 shows another form of my invention. The iron core C , consisting of a bundle of iron wires in the usual form, is wound around with 120 a few turns of heavy conductor, forming the coil P^2 . Well insulated from this is a coil of fine wire, the inner layers of which constitute the coil P , corresponding to the coil P' of Fig. 1, while the outer turns, which may be of 125 relatively smaller gage, are simply a continuation of the coil P , the terminal of this outer winding being at t^2 , while the other terminal t^2 of the outer winding is the same as that connected to the main circuit m . In this way 130 all of the finer winding around the core is effective as a source of electromotive force in maintaining the discharge between the terminals $t^2 t^2$, while a portion of the finer wind-

ing (of proper gage to convey the current) is used as the energizing-circuit. The coarse layer or winding is the substitute primary or the secondary primary. The whole structure may be immersed in a box of oil, as indicated by the dotted lines. If now current be passed in at m , it will traverse, say, eight or ten layers of the outer fine winding—that is, in the section P and reach-brush B' —and if segment G be in contact with the brush it will pass to segment G, thence back to connection n . During the period of contact the current will increase and highly magnetize the core C. When segment G breaks with brush B' , condenser-segment f touches brush B' , and the break is thus made with the condenser F across the gap; but this alone would not suffice to prevent damaging sparking, and therefore at or near the moment of breaking a circuit is completed by segment G^2 through brush B^2 and coil P^2 as a short circuit of low potential, thus instantaneously transferring the energy from coil P to the low-potential closed circuit. This transfer prevents sparking on the breaking of brush B' with segment G. The brush B^2 then leaves segment G^2 and ruptures the coarse-wire circuit, while condenser-segment f acts to connect condenser F across the new break thus formed. At this moment, however, the brush B' has reached the position shown in the figure between the condenser-segment f and segment G, being completely insulated. This is necessary on account of the high potentials developed in the circuit P, of which it is one terminal. The result of the sudden rupture of the circuit P^2 with condenser F across the break is to induce a vigorous high-potential charge in all of the fine wire from terminal t^2 to terminal t^3 , and according to the number of turns the length of spark produced may be determined. I have in this way, with cores of iron wire of about twelve inches long and one and one-half inches in diameter, obtained an induction of about three volts per turn, which with ten thousand turns would give thirty thousand volts. In such a case the turns impressed at $m\ n$ by a potential of one hundred and ten volts—that is, the turns included in the section P P—may equal thirty thousand. A coil in which the fine wire is twenty thousand turns may easily yield five-inch sparks between the terminals when operated according to my invention, the actual energy consumed from the circuit $m\ n$ being very slight, showing that the apparatus is working at good efficiency.

Fig. 7 indicates one way in which to more thoroughly insulate the brush B' , segment f , and segment G from each other at the time of rupture of the circuit in P^2 . To do so, they may be mounted in an oil-box, while the other portion of the apparatus—namely, brush B^2 and segment G^2 , with its corresponding segment f —may run outside thereof. This is to prevent sparking over the surfaces of the con-

tact breaking and making devices. The same effect is obtained, however, by enlarging the diameter of the break-piece upon which B' is used. This may readily be done, because the current which passes the brush B' is comparatively very small.

Figs. 8 and 9 show in diagram ways of connecting up the different parts when the arrangement is like that in Fig. 6. In Fig. 8 the line M goes to one end of the coil P, the circuit being completed through the break-pieces and brush B' , as in Fig. 6, the sparking terminals including the entire finer winding of the coil, as in that figure. The coil P^2 is also connected as in Fig. 6 and the condenser F is shown as in circuit around the coil P. Fig. 9 shows the same connections practically as in Fig. 8, the connection of the main m to the coil P being at the other end of that coil or to its junction with the finer winding included in the sparking circuit. Otherwise the connections in Fig. 9 are the same as those in Fig. 8 or in Fig. 6.

It is to be understood that various modifications of the arrangements may be made involving the same principles of operation. For example, properly-arranged vibrating break-pieces might be employed instead of rotating devices. In the same way, while a single core is shown, these parts may be changed or duplicated in the same system and will operate by sets of break-pieces or by a single break-piece in accordance with my invention; but these are obvious substitutions of equivalents. The discharges furnished by the apparatus of my invention may be employed to work vacuum-tubes, to produce ozone, or, in general, for any purpose to which such currents are applicable.

The foundation upon which my invention chiefly rests is the substitution of a well-closed secondary in intimate inductive relation with the energizing-primary energized at fairly high potential, such substitution being made at or about the time of rupture of the first or energizing circuit and such substitute coil having its circuit afterward broken while the current is vigorous.

What I claim as new, and desire to secure by Letters Patent of the United States, is—

1. The art of converting electric energy herein set out, which consists in energizing a coil at relatively high potential, breaking the circuit of the coil and at about the same time closing the circuit of a low-potential coil in inductive relation thereto, and then interrupting the current-flow in the second coil, thereby setting up in another coil the desired electromotive forces.

2. The art of converting electric energy herein set out, which consists in energizing by continuous current a coil at relatively high potential, breaking the circuit of the coil at the time of maximum current-flow, at about the same time closing the circuit of another coil in inductive relation thereto, and break-

ing the circuit of the second coil when it attains its maximum energy, thus setting up in another coil the desired electromotive forces.

3. An inductive device for converting electric energy, consisting of a primary wound for relatively high potentials, a secondary of low resistance, and another coil wound for high potentials, with means for suitably interrupting in sequence the circuits of the 10 first two coils.

4. An inductive device comprising a core, a primary coil wound for moderately high potentials, a secondary coil of low resistance, and a third coil wound for high potentials, 15 the primary coil and the third coil being electrically connected so that the entire finer winding of the coil is utilized to generate a high-potential charge.

5. In combination, mains carrying continuous current of relatively high potential, an inductive device comprising a primary fed from the mains, a secondary in inductive relation to the primary, and a third coil in inductive relation to the other two, with means 25 for interrupting the primary circuit and closing the normally open secondary circuit at about the same time.

6. In combination, mains carrying continuous current of relatively high potential, an 30 inductive device comprising a primary fed from the mains, a secondary of low resistance

and a third coil, the three coils in inductive relation on a common core, with means for breaking the primary circuit and closing the normally open secondary circuit at about the 35 same time, and for subsequently opening the secondary circuit.

7. In combination, mains carrying continuous current of relatively high potential, an inductive device comprising a primary fed 40 from the mains, a secondary of low resistance and a third coil, the three coils in inductive relation on a common core, with means for breaking the primary circuit closing the normally open secondary circuit at about the 45 same time, subsequently opening the secondary circuit, and for connecting a condenser across the terminals of the primary and secondary circuits at desired times.

8. An inductive device of the class described, comprising a core with three substantially independent windings thereon, means for opening and closing the circuits of two of the coils in succession, and means for throwing a condenser across the terminals of each 55 coil as it is opened.

In witness whereof I have hereunto set my hand this 23d day of February, 1897.

ELIHU THOMSON.
